UNITED STATES PATENT OFFICE.

CHARLES K. WOODIN AND WILLIAM W. SMITH, OF SPRINGFIELD, ILLINOIS.

GOLF PUTTING APPARATUS.

Application filed March 16, 1925. Serial No. 15,730.

Our invention relates to golf putting apparatus and more particularly to apparatus adaptable for use in the practice of putting.

The object of our invention is in the provision of a simple device that permits the practice of putting elsewhere than on a golf course.

Another object of our invention is in the provision of a putting apparatus of simple structure that approximates natural golf conditions with relation to the act of putting.

Yet another object of our invention is in the provision of a putting apparatus capable of slight adjustable to permit putting practice for a plurality of distances.

A further object of our invention is in the fashioning of a putting apparatus adjustable for the practice of puts of various lengths, said apparatus maintaining, at all times, the cup portion in a substantially horizontal plane.

A still further object of our invention is in the provision of putting apparatus that is adjustable to certain positions which, during practice, approximate similar putting conditions, and lengths of puts upon a normal golf green.

Other objects of our invention will appear in the following specifications taken in connection with the annexed drawings, in which:

Fig. 1, is a plan view from above of the putting device.

Fig. 2, is a side elevation of same showing the device in an adjusted position in dotted lines.

Fig. 3, is an enlarged detail of the cup and ejector member.

Fig. 4, is a cross sectional view taken on the line 4—4 of Fig. 2, and

Fig. 5, is a cross sectional view taken on the line 5—5 of Fig. 1.

Before referring to the drawings, it might be said that the present device is adapted for use in the practice of putting. The game of golf is of such common knowledge that it is not thought any description or rules of same need be given. However, the purpose of the present device is to increase the efficiency of a player in the putting stroke by permitting the practice of said stroke at

places other than upon the golf links. The present device is more particularly adapted for use in the home, club, etc., where it is placed upon a carpet for the purpose of approximating as nearly as possible, normal playing conditions. The player uses the same club, namely the putter, that he uses upon the golf links and also any ball that he desires.

For the reason that the ordinary carpet does not offer in any degree, the resistance of the ordinary green, it has been found necessary to resist in some manner, the movement of the ball towards the cup to approximate normal putting conditions. In the present device, this resistance has not only been taken care of but means has been provided for varying such resistance to permit practice of puts of various distances, while at the same time, the cup portion is maintained in substantially the same position that it would have upon the normal green, namely, level.

The present device is fashioned to approximate in substantially every detail, conditions similar to those on the natural golf green.

Referring to the drawings, a flexible sheet metal portion 10, provides the platform or resistance end 11, and a substantially flat portion 12, which will be referred to as the "green". This flexible sheet metal portion 10, is covered with a granulated cork fabric 13, which has a slightly yielding surface, and is utilized for the purpose of approximating as nearly as possible, the closely cut grass that normally covers a golf green. Surrounding the green portion 12, is a continuous up turned flange 14, which acts as a stop member for the ball when the putt is not successful and acts as a guide member for the return of same. Similarly an up turned flange 15 appears on either side of the resistance portion 11. The flange in this instance, however, being interrupted to permit flexing of this resistance portion in the adjusting action later to be described.

Means for supporting the putting green and resistance portion which is actually a part of the green, is provided in leg portions 16, pivoted at 17, to either side of the device and rearwardly thereof. Brace members 18,

5 pivoted at 19, at a point adjacent the forward end of the device and at 20, to the leg portion 16, provide means for holding the green and leg portions in assembled relationship. The pivotal relationship of the leg portions, cross rods and green member, permits adjustment of the inclination of the resistance portion and hence increasing or decreasing the angle of said portion.

10 In Fig. 2, the adjusting action is clearly disclosed and the means for setting the device in its plurality of positions, is shown as flexible index plates 21, secured at their upper ends to the flange or guide 14. These 15 index plates 21, contain thereon, a plurality of holes at the sides of which are indicated the length of putt that would approximate at least a similar length of putt upon an ordinary green. The placing of these holes 20 was fixed definitely after exhaustive tests of the angle of inclination of the resistance portion in comparison to puts of various distances upon an ordinary golf green. A rivet 22, is attached to the leg portion 16, and protrudes inwardly in such manner as 25 to be adapted to coincide with any of the holes above mentioned.

20 In other words, by a movement of the leg portions 16, and consequent movement of the 25 flexible resistance or green portion 11, through the cross rods 18, any elevation of the device desirable may be obtained and the location of the device in a fixed position is accomplished by the insertion of the rivet 30 22, into the proper hole in the flexible index sheet 21.

40 Disposed at a point intermediate the sides of the device, and in the middle of the substantially flat green portion 12, is a cup 23. This cup is made of sheet metal and is securely attached to the flexible sheet member 10, as shown at 24, in Fig. 3. This cup member acts to receive the ball as it does upon a natural golf green. Means for 45 ejecting the ball from the cup is provided in a lever 25, the same being pivoted in brackets 26 attached to either side of the device, as well as an ejector portion 27 disposed within the cup 23, and attached 50 as at 28, to the fulcrumed end 29 of the lever 25. The slot 30 in the sheet metal cup permits up and down movement of the portion 29 of the ejector mechanism.

55 It is obvious that downward movement of the lever 25 will result in upward movement of the portion 27 and consequently ejection of the ball from the cup. It might be said at this time that although the green portion 12, containing the cup member 23, is substantially level, nevertheless, a very slight inclination of same towards the resistance portion is necessary for the return of the ball in case the putt is unsuccessful. This inclination is very slight and is only sufficient to return the ball to the resistance

portion which is inclined sharply as may be clearly seen, and will act to return the ball to the player. It might also be added that the green portion 12 is maintained in a substantially level position at all times irrespective of the adjustment feature. 70

75 In view of the detailed description of the putting apparatus, no description of the operation of same is thought necessary other than the varying of the inclination of the resistance portion to change the length of putt. The player varies his practice by this adjustment mechanism and does not change his position relative to the putting apparatus which is approximately 6 feet 80 away. It may be seen from the above that the player may practice the act of putting under almost similar conditions to that of the ordinary golf green, and that he may vary his practice for various lengths of 85 puts with a knowledge of the length of the putt he is making.

90 Actual putting conditions on a normal golf green have been carried even to the extent of having the ball stay in the cup after a successful putt, so that the player may see it. However, to facilitate practice, the ejector mechanism is provided for the ready removal of the ball from the hole, and its return down the resistance portion 95 to the player.

What we claim is:

1. In a device of the class described, a golf putting practice apparatus, comprising a green portion, a cup member disposed therein, a resistance portion leading to the green portion, and means for changing the angle of inclination of the resistance portion for the purpose of varying the putting practice. 100

2. A golf putting apparatus, comprising a substantially level green portion, a cup member disposed therein, a flexible resistance portion leading to said green member, and adjustable mechanism for varying the inclination of said flexible portion. 110

3. A golf putting apparatus comprising an elevated substantially level green portion, a cup member therein, a flexible resistance portion leading to said green member and mechanism attached to the green portion as well as the resistance portion, and adapted to vary the inclination of said resistance portion while maintaining the green portion in a substantially level position. 115

4. A golf putting apparatus comprising a substantially level green portion, a cup member therein, a flexible resistance portion leading to said green member, adjustment mechanism for varying the inclination of said flexible portion and an index portion for permanently fixing and indicating the inclination of said resistance portion. 125

5. A golf putting apparatus comprising a substantially level green member, a cup 130

member disposed therein, a resistance portion leading to said green member and means for ejecting a ball from the cup member including an ejector in the cup member and a pivoted lever for operating same.

5 6. A golf putting apparatus comprising a substantially level green member, a flexible resistance portion leading thereto, stop

and guide members surrounding the green and resistance portions, a cup disposed in the green member, an ejector in the cup member and a lever for operating same.

10 In testimony whereof we affix our signatures.
